CLAIM

The ornamental design for a portion of a shelf divider wall, as shown and described.

DESCRIPTION

FIG. 1 is a top perspective view of a portion of a shelf divider wall;

FIG. 2 is a right side elevation view of the shelf divider wall; the left side elevation view being a mirror image thereof;

FIG. 3 is a front elevation view of the shelf divider wall of FIG. 1;

FIG. 4 is a back elevation view of the shelf divider wall of FIG. 1; and,

FIG. 5 is a bottom elevation view of the shelf divider wall of FIG. 1.

The dashed broken lines in FIGS. 1-5 represent environmental subject matter and form no part of the claimed invention.
